UNITED STATES PATENT OFFICE.

GEORGE A. LOWRY, OF BOSTON, MASSACHUSETTS.

FABRIC.

No. 918,683.

Specification of Letters Patent. Patented April 20, 1909.

Application filed April 3, 1905. Serial No. 253,541.

To all whom it may concern:

Be it known that I, GEORGE A. LOWRY, a citizen of the United States, residing at Boston, in the county of Suffolk and State of Massachusetts, have invented a new and useful Fabric, of which the following is a specification.

This invention relates to fabrics having the body thereof composed of grass, hay, straw, piles, withes, cane, bamboo, or other similar or suitable material, and method of making the same.

The object of the invention is to produce a fabric which is simple in construction, and wherein the body portion is of even density and thickness throughout, which is yielding, and presents a smooth, even bearing surface, and wherein the employment of needles in applying the warp to hold and maintain the integrality of the body portion, or of the filling material composing the same, together, is avoided.

A further object of the invention is to produce a fabric of the character referred to, wherein the body portion is held or bound together by suitable binder threads applied thereto in a manner to secure an efficient binding effect throughout the body portion, and without any weaving operation in the production of the body portion, and without any stitching or needle operation in the application of the binder threads.

A further object of the invention, in a more specific statement thereof, is to produce a fabric of the character referred to, wherein the body portion is held or bound together by suitable binder threads applied in parallel relation with respect to each other to both sides or surfaces of the body portion of the fabric, and extending in the direction of the length of the fabric, with a transversely extending locking binder thread passed respectively over and under corresponding parallel binder threads applied respectively to the surfaces of the fabric, and in such manner as to bind or secure adjacent increments or portions of the body portion of the fabric.

A further object of the invention is to utilize waste grass, hay, straw, bamboo, cane, withes, or the like, or similar material which is unfit for other use, in the manufacture of useful commodities such as mats, rugs, carpets, matting, or other fabrics.

A further object of the invention is to utilize, in the manufacture of fabrics of the class

referred to, material of the nature mentioned, whether such material is first formed or spun into twine condition or not.

Other objects of the invention will appear more fully hereinafter.

The invention consists substantially in the construction, combination, location and mode of operation, all as will be more fully hereinafter set forth, as shown in the accompanying drawing, and finally pointed out in the appended claims.

Referring to the accompanying drawing, and to the various views and reference signs appearing thereon,—Figure 1 is a top plan view of a portion of fabric constructed in accordance with the principles of my invention, and illustrating the manner of application of the binder threads to the body thereof. Fig. 2 is a sectional view of the same on the line 2, 2, of Fig. 1, looking in the direction of the arrows. Fig. 3 is a similar view on the line 3, 3, of Fig. 1, looking in the direction of the arrows. Fig. 4 is a view similar to Fig. 1, illustrating a modified construction embraced within the spirit and scope of my invention.

The same part is designated by the same reference sign wherever it occurs throughout the several views.

In various sections throughout the country are vast areas of marsh land upon which is grown immense quantities of marsh grass, and in certain sections of the country throughout wide areas vast quantities of straw are produced, especially in the wheat-growing sections of the country, and which straw is burned or otherwise destroyed in order to get rid of it. In other sections of the country are grown bamboo, cane, withes, piles, or the like, which has been utilized to a greater or less extent by weaving the same or otherwise producing merchantable and household commodities. In efforts heretofore made to utilize marsh grass, straw, and the like, the stems, stalks or spears of the grass or straw have been formed into twine, and the twine has been woven into fabrics, mats, rugs, carpets, and the like. Much the larger part of the vast quantities of marsh grass, straw, piles, bamboo, cane, and the like, available for use in the manufacture of useful and merchantable commodities, is unsuitable for utilization by first spinning or forming the same into twine condition, while some of these materials may be readily formed or spun into twine.

The material which is unsuitable for utilization in this manner, by reason of the joints in the stems, stalks or spears, requires preliminary manipulation in order to work the 5 same into twine or to weave the twine into fabrics. Moreover, in the production of a fabric of the character referred to, and employing materials of the nature mentioned, it has been the custom to employ weaving 10 operations necessitating the use of needle or shuttle mechanisms, by which the twine is first wound into cops, which are inserted in the shuttles which in the loom mechanisms are thrown back and forth to form the 15 weft portion of the fabric. Ordinarily, twine made from the materials mentioned is bulky, and only comparatively small quantities or lengths can be conveniently employed on the cops so employed or used. 20 Consequently it becomes necessary to frequently renew the cops in the shuttles and to splice the ends of the twine forming the weft of the material of the fabric, and hence necessarily reducing the speed of production of the fabric. 25

In accordance with the principles of my invention, I propose to produce a fabric having a body portion composed of a material, whether first formed into twine or not, 30 and of even thickness throughout, the body portion being efficiently held or bound together by binding threads, without the employment of binding or warp threads, applied thereto in proper manner, and wherein 35 the use of shuttle mechanism to form the weft material may or may not be employed, thereby producing an exceedingly simple, durable and inexpensive fabric.

In carrying out my invention, I propose 40 to condense the stems, stalks, spears, piles, canes, withes, or the like, into the form of a flattened mass or matting of substantially equal thickness and density throughout, and of substantially the ultimate width of 45 the fabric to be produced, and preferably, though not necessarily, with the stems, stalks or spears, bamboos, canes, withes, or the like, composing the body portion, in substantially parallel relation with respect 50 to each other, and whether first or preliminarily formed into twine condition or not, thereby forming the body portion of the fabric, and I propose to suitably unite or bind together the body portion thus formed 55 by applying thereto suitable binder or warp threads, and one of the important features of my present invention is the manner of applying the warp or binder threads so as to efficiently bind the body portion into an 60 integral fabric. In this manner I produce an exceedingly smooth, simple and durable fabric, the body portion of which is rendered soft and flexible and yielding, and which may be produced with great economy and 65 in unlimited quantity, inasmuch as the

material composing the body portion is available in practically unlimited quantities for such use, and at all seasons of the year.

Referring to Figs. 1, 2 and 3, the body portion of the fabric is composed of material of the character referred to, the successive portions of which are designated by reference sign A. Each portion A of the body of the fabric may comprise one or more stems, 70 stalks, spears, piles, bamboos, withes, canes, or the like, arranged, preferably, though not necessarily, in parallel relation with respect to each other in each bunch or portion A thereof, the successive bunches or portions A 75 being arranged or placed in parallel relation with respect to each other. Applied to each side or surface of the body portion, is a series of binder threads B C, the binder threads B being applied to one side or surface of the 80 body, and the binder threads C to the other or opposite side or surface of the body. The binder threads B are arranged in parallel relation with respect to each other, and extend in a direction transverse to the length of the 85 portions A composing the body, while in similar manner the binder threads C are applied to the opposite surfaces of the body, and in parallel relation with respect to each other and with respect to the binder threads 90 B, and transversely across the body portions A, as clearly shown in the drawing. As shown, and preferably, though not necessarily, the binder threads C and B are arranged 95 out of the same plane with respect to each other—that is, in alternating relation with respect to planes intersecting the portions A 100 of the body at right angles. The binder threads B C applied to opposite sides or surfaces of the body are locked together and between adjacent body portions A by means of a locking binder thread D, which, as shown, and preferably, is passed over a binder thread 105 B applied to one surface of the body, and thence under the binder thread C adjacent thereto applied to the opposite side or surface of the body, thence over the next adjacent binder thread B and under the next adjacent binder thread C, and so on, transversely across the fabric and in parallel relation with respect to the portions A of the 110 body. It is obvious that this manner of application of the binder threads may be carried out in a most simple and efficient manner by building up the body portion of the 115 fabric by means of successive increments, each increment comprising one or more of the stems, stalks, bamboos, or the like, and whether first formed into twine or not, and previous to the application of each successive increment, deflecting all of the binder threads B over the outside edge of the last increment 120 toward the plane of the binder threads C, and similarly deflecting all of the binder threads C over the same edge and toward the plane 125 130

of the binder threads B, thereby causing the binder threads B and C to temporarily cross each other after the preceding increment has been added to the body portion thereby 5 crossing at a point intermediate their upper and lower faces. With the binder threads B C thus crossed, the locking thread D is passed through the bights or crotches formed by the crossed binder threads B C preferably by 10 means of a shuttle, in the same manner as in a loom. The binder threads B C are then returned or restored to their initial positions, being held or locked around the last increment or portion A of the body portion to be 15 applied by the locking binder threads D. The next increment or portion of the body is then applied or dropped in between the binder threads when the latter are not crossed, and the operation above described, 20 of shifting the binder threads B C into crossed relation and the application through the bights or crotches formed by the crossed threads of the locking thread D, is repeated, and the operation proceeds, thereby success- 25 sively building up the body portion of the fabric by successively adding thereto increments of material to form such body portion, and whether such increments are in spun or twine condition or not.

30 In Fig. 4, I have shown a fabric in which the material forming the body portion is first formed in any well known manner, into twine condition A', the binder threads B C D remaining the same as in the example illus- 35 trated in Figs. 1, 2 and 3, and being applied in identically the same manner, the difference being that in the form shown in Figs. 1, 2 and 3, the material forming the body portion of the fabric is not preliminarily formed 40 into twine condition, while in the construction shown in Fig. 4, such material is first formed into twine condition, and the successive additions of increments of the material to form the body portion being effected by 45 bending successively back and forth upon itself the twine into which the material is first preliminarily formed. With this operation, it is obvious that the twine thus bent or doubled back and forth upon itself may be in the 50 form of a large ball, instead of upon a cap, for a loom mechanism of the ordinary construction, thereby not only avoiding the necessity for frequent renewals of the cops, but also facilitating the formation of the fabric, and 55 reducing the time necessary to effect the fabric-forming operation, it being understood that the binder threads B C are shifted or moved into crossed relation with respect to each other over and around each successive 60 strand of the completed twine, and the locking thread C passed through the bights or crotches formed by the crossed threads B and C, and then the binder threads B and C returned or restored to initial position before 65 the twine forming the body portion is again

laid into the body of the fabric by being bent back upon itself.

Of course it will be understood that when the binder threads B and C are restored to initial position after having been crossed or 70 arranged in crossed relation, and after the binder thread C has been passed through the bights or crotches formed by crossing such threads, the binder threads B and C are snugly stretched or pulled down below, or 75 substantially below, the side surfaces of the fabric, through the tension under which the binding threads are applied, and as clearly shown in the drawing. Consequently, the wear imposed upon the fabric in use is taken 80 largely upon the material forming the body portion of the fabric, instead of upon the binding threads, and in any event the locking threads D are drawn down into the body of 85 the fabric between adjacent increments thereof, so that they are protected against wear, and any break that might occur in any one of the binding threads B or C would have but little if any effect upon the fabric.

It is obvious that variously colored binder 90 threads may be employed so as to impart to the finished product any desired or varie- 95 gated pattern or ornamental appearance. It will be seen from the foregoing description that I produce an exceedingly simple and 95 efficient and economical fabric, utilizing waste products for the purpose, and producing a commodity which is soft, pliable and durable.

Having now set forth the object and na- 100 ture of my invention and the method of car- 105 rying the same into practical operation and having specifically described the process for manufacturing and the construction of the article resulting from such process, it is to be understood that although the present appli- 105 cation is limited to the article itself the method or process for producing the same is reserved for a separate application, but

What I claim in the present application and desire to secure by Letters Patent is— 110

1. As a new article of manufacture, a fabric having a body portion condensed or compacted into flattened mat formation, and having binder threads arranged in parallel relation with respect to each other and on 115 opposite sides or surfaces of the body por- 120 tion, and having a portion of the binder threads drawn into the body of the mat by a locking thread extending transverse to the binder threads and respectively over and under corresponding binder threads lying on op- 125 posite sides of the body portion.

2. As a new article of manufacture, a fab- 125 ric having a body portion composed of por- 130 tions arranged in parallel relation with respect to each other, binder threads arranged on opposite surfaces of the fabric and trans- 135 verse to the length of the body portions, and with a portion thereof deflected between the body portions by locking threads arranged 140

intermediate said body portions and passing respectively over and under the binder threads lying on opposite surfaces of the body.

5. As an article of manufacture, a fabric having a body portion composed of portions of uniform thickness arranged in parallel relation and within the same plane with respect to each other, binder threads arranged 10 on opposite surfaces of the body and transverse to the length thereof, the threads on one surface being offset with respect to the threads on the other surface, and locking threads arranged between the body portions 15 and engaging the binder threads.

4. As an article of manufacture, a fabric having a body portion composed of portions of uniform thickness arranged in parallel relation and within the same plane with 20 respect to each other, binder threads arranged on opposite surfaces of the body and transverse to the length thereof, the threads on one surface being offset with respect to the threads on the other surface, and locking threads arranged between the sections and engaging the binder threads.

5. As an article of manufacture, a fabric 30 having a body composed of portions of uniform thickness arranged in parallel relation within the same plane with respect to each other, binder threads arranged on opposite surfaces of the body and transverse to the 35 length thereof, the threads on one surface being offset with respect to the threads on the other surface, and locking threads arranged between the body portions and extending transverse to the binder threads and respectively over and under corresponding binder threads lying on opposite sides of the body portions.

6. As an article of manufacture, a fabric

having a body formed of a continuous strip of fibrous material of uniform thickness and 45 bent to form sections of uniform lengths located in the same plane with respect to each other, binder threads arranged on opposite surfaces of the fabric and transverse to the length of the sections, and locking 50 threads arranged between the sections and engaging the binder threads.

7. As an article of manufacture, a fabric having a body formed of a continuous strip of fibrous material of uniform thickness and 55 bent to form sections of uniform lengths located in the same plane with respect to each other, binder threads arranged on opposite surfaces of the fabric and transverse to the length of the sections, the threads on one surface being offset with respect to the threads on the other surface, and locking threads arranged between the sections and engaging the binder threads.

8. As an article of manufacture, a fabric 65 having a body formed of a continuous strip of fibrous material of uniform thickness and bent to form sections of uniform lengths located in the same plane with respect to each other, binder threads arranged on opposite 70 surfaces of the fabric and transverse to the length of the sections, the threads on one surface being offset with respect to the threads on the other surface, and locking threads arranged between the sections and engaging the binder threads, portions of the 75 binder threads being drawn between the sections and below the surfaces thereof by the locking threads.

In witness whereof, I have hereunto set my 80 hand this 29th day of March 1905, in the presence of the subscribing witnesses.

GEORGE A. LOWRY.
